UNITED STATES PATENT OFFICE.

H. CLAY BASCOM AND CYRUS A. HODGES, OF TROY, NEW YORK, ASSIGNEES
TO JOHN RONEY, OF PITTSBURG, PENNSYLVANIA.

DESIGN FOR A COOKING-STOVE.

SPECIFICATION forming part of Design No. 15,138, dated July 15, 1884

Application filed May 13, 1884. Term of patent 7 years.

To all whom it may concern:

Be it known that we, H. CLAY BASCOM and CYRUS A. HODGES, citizens of the United States, residing in the city of Troy, in the county of Rensselaer and State of New York, have jointly invented and produced a new and original Design for Cooking-Stoves, of which the following is a specification, reference being had to the accompanying cut, print, or engraving, illustrating our said new design.

This design embraces several new and distinct parts and combinations of parts which go to make up the whole design, as shown in the accompanying illustration and herein-
15 after described.

The design for the shelf-supporting plate A consists of the ornamental curved and angular end edges, *a*, and the intermediate row of separate compound ornaments, *b*, all shaped
20 and arranged together so as to present substantially the same appearance as is represented in the aforesaid print.

The design for the front door, B, is composed of the upper part, C, having its front curved
25 convexly from top to bottom, and three broad mica-light apertures, *e*, and ornaments *c'*, and the lower portion, D, having the narrow draft-openings *d* and intermediate ornaments, *d'*, all shaped and arranged so as to appear sub-
30 stantially as illustrated in the aforesaid cut.

The design for the oven-door E consists of the rectangular border *e*, the panel *f*, curved convexly from top to bottom, and having inclined or beveled ends *f'*, and the compound
35 border ornaments *g*, all shaped and arranged together substantially as represented in the accompanying engraving.

The design for the separable oblong ornamental plate F consists of its top and bottom
40 scroll-curved edges, *h*, with angles *h'*, the angular end edges, *i*, the middle name space or part, *j*, and the intermediate polished surface, *k*, having ineut ornamentalations, all shaped and arranged together substantially as shown
45 in the aforesaid print.

The design for each distinct door and panel G G' G'' consists of the raised rectangular border *l*, surrounding the surface *m*, that is curved convexly from top to bottom, and has the in-
50 clined ends *m'*, the central ornament, *n*, and

the border ornaments *o*, all shaped and arranged together substantially as shown in the accompanying cut.

The design for the side of the stove-body consists of the plate H and the raised rectangular doors and panel F G G', all shaped, ornamented, and arranged so as to present substantially the same appearance shown in the aforesaid engraving.

The design for the side plate, I, of the rear extension consists, essentially, of the raised rectangular ornamental panel G', compound ornament *p*, and curved lower edge *q*, all shaped and arranged so as to appear substantially as represented in the aforesaid cut.

The design for the base-frame consists of the side plate, J, having the middle ornament, *r*, and ornamental lower edge *s*, the end plate, K, having the middle ornament, *t*, and ornamental lower edge *u*, and the corner parts, L,
70 having the ornament *v*, all shaped and arranged together so as to appear substantially as represented in the accompanying illustration.

The design for the legs M consists of the narrow curved part *w*, upper downwardly-tapering convex portion, *x*, having the ornamental side edges, *y*, and the middle compound ornament, *z*, all shaped and arranged as shown
75 in the accompanying print.

We claim as our design—

1. The design for the shelf-supporting plate A, embracing the edge parts, *a*, and ornaments *b*, all shaped and arranged as set forth.

2. The design for the front door, B, composed of the parts C c c' and D d d', all shaped and arranged together as described.

3. The design for the oven-door E, consisting of the rectangular border *e*, curved panel *f*, with inclined ends *f'*, and the compound border ornaments *g*, shaped and arranged together as set forth.

4. The design for the distinct separable ornament or plate F, composed of the ornamental top and bottom edges, *h h'*, end edges, *i*, name-space *j*, and ornamented surface *k*, all shaped and arranged as shown and described.

5. The design for the door and panels G G' G'', composed of the parts *l*, *m*, *m'*, *n*, and *o*, all shaped and arranged as set forth.

6. The design for the stove-body, composed of the plate II and the doors and panel F G G', shaped, ornamented, and arranged together as set forth.
- 5 7. The design for the plate I of the rear extension, composed of the ornamented panel G² and the ornamental parts p and q, shaped and arranged as set forth.
8. The design for the base frame, composed 10 of the parts J r s, K t u, and L v, shaped and arranged together as set forth.

9. The design for the legs M, composed of the parts w x y z, shaped and arranged as shown and described.

In testimony whereof we hereunto set our 15 hands, in the presence of two subscribing witnesses, this 10th day of May, 1884.

H. CLAY BASCOM.
CYRUS A. HODGES.
